ATTORNEY.

UNITED STATES PATENT OFFICE.

ALFRED A. LOVEJOY, OF SOUTH BEND, INDIANA.

DESIGN FOR A TOWEL-HOLDER.

57,058.

Specification for Design.

Patented Feb. 1, 1921.

Application filed August 14, 1920. Serial No. 403,613. Term of patent 14 years.

To all whom it may concern:

Be it known that I, ALFRED A. LOVEJOY, a citizen of the United States, residing at South Bend, in the county of St. Joseph and State of Indiana, have invented and produced a new, original, and ornamental Design for a Towel-Holder; and I do hereby declare the following to be a full, clear, and exact description of the same, reference being had to the accompanying drawing, forming a part thereof.

Fig. 2 is a side elevation thereof.

What is claimed is:

The ornamental design for a towel holder as shown.

In testimony whereof I affix my signature.

ALFRED A. LOVEJOY.
